UNITED STATES PATENT OFFICE.

GEORGE C. WHITLOCK, OF OMAHA, NEBRASKA.

ANCHORING BEAMS TO WALLS AND TRUSS AND GIRDER BEAMS.

SPECIFICATION forming part of Letters Patent No. 443,657, dated December 30, 1890.

Application filed April 15, 1890. Serial No. 348,040. (No model.)

To all whom it may concern:

Be it known that I, GEORGE C. WHITLOCK, a citizen of the United States, residing at Omaha, in the county of Douglas and State 5 of Nebraska, have invented a new and useful Improvement in Anchoring Beams to Walls and Truss and Girder Beams, of which the following is a specification.

My invention relates to anchoring the beams 10 to partition and other walls and truss or girder beams by means of longitudinal bar-iron rails masoned and anchored to the longitudinal walls, truss, or girders, and by said rails having an upward tongue or web, over which 15 the floor-beam with a lateral groove at the seat of its end matches and is thereby anchored to the wall.

In the annexed drawings, Figure 1 represents a horizontal section of a brick building 20 at a floor, with a construction of anchoring the beams to the walls and girders according to my improvement. Fig. 2 is a vertical lateral section of such construction, showing only the portions of the walls and building connected with the floor-beams. Fig. 3 is a horizontal section of the same. Fig. 4 is a detached vertical lateral section of the anchoring rail or bar and showing the joint of the floor-beam and end with it. Figs. 5 and 6 are a 25 detached vertical and horizontal section showing the invention applied to the wall, which is built with a projecting brick saddle or ledge for the floor-beams to rest upon.

A A represent the outside longitudinal walls, 35 B B the front and rear walls, C a girder-beam, and C' a partition-wall, of a building.

D represents the floor-beams.

At the designated level of the base for the floor-beams along the longitudinal walls A 40 are masoned the horizontal bar iron or rails E, flush with the inner sides of said walls, which rails have an upward tongue F along said inside of the wall and extend from and into the front and rear walls B B, and in the 45 center of said each rear and front walls is masoned a flat bar G, which overlaps with its ends both the rails E employed in the two longitudinal walls A A. The meeting ends of the bars G with the ends of the rails E are 50 connected by bolts or rivets H, and the rails E are also secured to their walls by lateral anchors I I, of which a number is provided a

suitable distance apart along each rail to lock it to the wall, and each engaging with a hook end into an opening made in the rail and 55 having longitudinal bent legs masoned in the wall, as shown. The floor-beams have each a lateral groove J, cut in the resting-seat of the beam and engaged by the wall and rail E. Said groove in the beam end engages over 60 the tongue of the rail, and the beam is thereby anchored to the wall. When a partition-wall C' is employed between the sidewalls A A, such a rail E is laid and masoned at such level on each side of said partition-wall, as shown, 65 and a double-hooked clamp-anchor K is used, connecting the two rails together by the hooks on its ends engaging in openings in the rails, as shown in Figs. 2 and 3. When a girder-beam is used in the building between 70 its side walls, as shown in Figs. 2 and 3, the rail E' has a central tongue or rib F', and the beams to each side of the girder engage both with their grooves J over the tongue F', as shown. With the beams and floors, where 75 much strain is trusted to them, I protect the beam ends from splitting by means of flat iron straps L, which are employed on the opposite longitudinal sides of each beam end, and by bolts or nails through the beam end 80 and said straps the beam end is clinched between. Said straps have also the grooves J to lock over the ribs F. With girder-beams the rail E' is spiked or nailed to the girder-beams. 85

In buildings in which the walls have a projecting brick saddle or ledge A' to rest the floor-beams, as shown in Fig. 5, the rail E is placed upon the said saddle or ledge, and by means of anchors I engaging in the rail and 90 being made with a hook to lock in the wall and masoned in the same, the beams are anchored to the wall. With a proper number of equally-distributed anchors I the rail E is held upon said saddle or ledge and the 95 floor-beams, with the grooves J at their seats locking over the ribs F of the rail, whereby the walls are anchored to the floor-beams.

In buildings where the girder-beams rest upon brick pier or buttress A'' on the end walls, 100 as shown in Fig. 6, the ends of the rail E' are anchored to the walls by clamp-anchors K', of which one end engages in the rail end E' and the other end has a hook which is masoned

in the wall. Where the floor beams and girders do not rest upon a saddle or ledge A' formed on the wall, the beam ends enter the wall. Said beam ends are cut slanting, as shown, to allow in case of fire the beam ends to drop out of the wall without breaking the wall. (All shown in dotted line in Fig. 2.)

What I claim as my invention, and desire to secure by Letters Patent, is—

- 10 In anchoring floor-beams, girders, and other beams to walls, the combination of bars or

rails E, having an upward tongue, web, or rib F, anchored to and masoned in the walls or anchored to the girder-beam and the floor or roof beam, provided with a lateral groove J to lock over said rib or tongue F, substantially as and for the purpose herein set forth.

GEO. C. WHITLOCK.
